UNITED STATES PATENT OFFICE.

LEON L. RUSSELL, OF GREENE, IOWA.

LACING-STUD.

SPECIFICATION forming part of Letters Patent No. 704,118, dated July 8, 1902.

Application filed April 24, 1902. Serial No. 104,554. (No model.)

To all whom it may concern:

Be it known that I, LEON L. RUSSELL, a citizen of the United States, residing at Greene, in the county of Butler and State of Iowa, 5 have invented new and useful Improvements in Lacing-Studs, of which the following is a specification.

My invention consists of an improved lacing-stud designed more particularly for use 10 on ladies' shoes; and its novelty, utility, and advantages will be fully understood from the following description and claims when taken in conjunction with the accompanying drawings, in which—

15 Figure 1 comprises the front portions of a shoe-upper equipped with my improved studs, said studs being shown as they normally appear. Fig. 2 is a transverse section illustrating two of the studs as they appear when the 20 lace in engagement therewith is drawn taut. Fig. 3 is a perspective view of one of the studs removed.

Similar letters of reference designate corresponding parts in all of the views of the drawings, referring to which—

25 A A are the front portions of the upper of a lady's shoe, B a lace, and C C my improved lacing-studs. The studs are similar in construction, and therefore a detailed description 30 of the one shown in Fig. 3 will suffice to impart an understanding of all. Said stud C comprises a metallic eyelet D, which may be fixed in or on a shoe-upper portion or other article to be laced in the ordinary or any other 35 approved manner, and a hook E. The hook, which is formed of spring-steel or other material suitable to the purpose of the invention, is fixed at one end to or formed integral with the eyelet A, is shaped to form a curved loop 40 a and bights b c in rear of and below said loop, and has its opposite end, which forms the terminal of the bight c, free, as indicated by d. The side of the loop a adjacent to the bight b is of a reduced thickness, as is also the bight 45 of said loop, this in order to increase the resiliency or springiness of the loop. By virtue of this increased springiness and the fact that the bight c and free end d are normally disposed in advance of the bight b it will be ob- 50 served that when the lace is engaged with the bights b c after the manner shown in Fig. 2 and drawn taut the bight c will be drawn rear-

wardly or inwardly, as will also the loop a, which normally overhangs the eyelet D, with its bight immediately adjacent to the same. 55 This will result in the bight of the loop a or, in other words, the free end of the hook being drawn down into the eyelet D, as shown in Fig. 2. In such position the hook end will be guarded by the eyelet and effectually prevented from catching into and tearing the lace with which ladies' skirts are ordinarily trimmed; also the lace will be securely held against casual disengagement from the hook. 60

In practice my improved studs are applied 65 to the upper portions A of a lady's shoe in the ordinary manner, as shown in Fig. 1, and when the shoe is to be laced the lace B is engaged with the hooks E and drawn taut, when the free ends of the hooks will be drawn into 70 their complementary eyelets for the purpose stated. When the lace is untied or otherwise released and loosened, the free ends of the hooks will spring out of the eyelets and assume their normal positions, as will also the 75 bights c, the latter slightly in advance of the bights b.

When the hooks of the studs are in their normal position, it will be observed that a lace may be engaged therewith very quickly 80 and easily by simply passing it between their free ends and the eyelets.

While designed more particularly for use 85 on ladies' shoes, I desire it distinctly understood that my improved stud may be used in other connections to which it is applicable with advantage without departing from the scope of my invention.

I have entered into a detailed description 90 of the present and preferred embodiment of my invention in order to impart a full, clear, and exact understanding of the same. I do not desire, however, to be understood as confining myself to the specific construction and relative arrangement of the parts as shown 95 and described, as such changes or modifications may be made in practice as fairly fall within the scope of my claims.

Having described my invention, what I claim, and desire to secure by Letters Patent, 100 is—

1. A lacing-stud comprising an eyelet, and a spring-hook connected at one end to the eyelet and overhanging the same, whereby, when

the bight of the hook is subjected to draft, the free end thereof will be drawn down into the eyelet.

2. A lacing-stud comprising an eyelet adapted for connection to a shoe-upper or other article to be laced, and a hook overhanging the eyelet; the said hook being formed of spring metal, and having one end fixed to the eyelet, and its other end free, and also having the loop *a*, the bight *b* disposed in rear of and below the loop, and the movable bight *c* also disposed in rear of and below the loop, and normally in advance of the bight *b*.

3. A lacing-stud comprising an eyelet adapted for connection to a shoe-upper or other article to be laced, and a hook overhanging the eyelet; the said hook being formed of spring metal, and having one end fixed to the eyelet, and its other end free, and also having the

loops *a*, a portion of which is of reduced thickness, the bight *b* disposed in rear of and below the loop, and the movable bight *c* also disposed in rear of and below the loop, and normally in advance of the loop *b*.

4. The combination of a shoe-upper or other article to be laced, a spring-hook connected at one end thereto, and means on the upper or other article to be laced, fixed with respect to the hook, and adapted when the hook is placed under tension to guard the free end thereof.

In testimony whereof I have hereunto set my hand in presence of two subscribing witnesses.

LEON L. RUSSELL.
